UNITED STATES PATENT OFFICE.

CHARLES B. GOODSPEED, OF COLUMBUS, OHIO.

TRUCK SIDE FRAME.

No. 884,726.

Specification of Letters Patent. Patented April 14, 1908.

Application filed January 11, 1908. Serial No. 410,348.

To all whom it may concern:

Be it known that I, CHARLES B. GOODSPEED, citizen of the United States, residing at Columbus, in the county of Franklin and State of Ohio, have invented certain new and useful Improvements in Truck Side Frames, of which the following is a specification.

My invention relates to the improvement of car truck side frames and journal boxes which are adapted to be used in conjunction therewith and the objects of my invention are to provide an exceedingly strong and at the same time inexpensive construction of truck side frame; to so construct my improved truck frame and the journal boxes therefor, as to permit of the journal boxes being readily connected with or detached from the truck side frames, thus obviating the difficulties usually experienced in securing a perfect casting where the boxes and side frame are cast integral and also to provide improved means of securing the boxes rigidly in connection with the frame without the employment of bolts or similar attaching devices. These objects I accomplish in the manner illustrated in the accompanying drawing, in which:

Figure 1 is a side elevation of the car truck frame showing the journal boxes and car wheels in connection therewith, Fig. 2 is a plan view of the same, and, Fig. 3 is a sectional view on line x—x of Fig. 1 showing the car wheel and its journal in elevation.

Similar numerals refer to similar parts throughout the several views.

1 represents one of my improved integrally cast side truck frames, which at the center of its length and at its point of greatest height is formed with a bolster receiving opening 2 in which the end of a bolster 3 is mounted upon spring 4.

Each end or bearing head 1^a of the truck frame is preferably formed as shown, of a substantially oval shape and within each of said oval terminations is a correspondingly shaped opening as indicated at 5, the longer diameter of said opening being represented by a line drawn vertically through the axis thereof. As indicated at 6 in Fig. 3 of the drawing, I form in the head or bearing end 1^a at the lower side or end of the opening 5, a recess or offset, while a similar recess or offset 7 is formed in said head at the upper side of the inner mouth of the opening 5. 8 55 represents a car wheel and 9 the projecting

journal thereof which is of the usual form and construction.

10 represents a journal box which is substantially oval in cross section and the body of which is of such form as to admit of its fitting detachably within the opening 5 of the truck frame end or head. This journal box is provided with the usual forward extension, the front of which is adapted to be closed in the usual manner by a hinged door 11. In the construction of the journal box, I form on the lower side thereof toward the front end, a downwardly projecting lug 12 and a similar lug 13 is formed on the upper side of said journal box toward the rear end thereof. 70 The journal box thus formed incloses the usual metallic packing or wearing brass 14. In connecting the box with the truck frame end, it will be understood that said box is designed to be inserted into the opening 5 from the outer end thereof and owing to the formation of the projecting lugs 13 and 12 on the box, it is obvious that the latter must while being inserted, be tilted to such angle as to prevent the lug 13 from contacting with the head or frame end until the box has been forced inward a sufficient distance to permit it being dropped to a horizontal position, thereby causing an engagement of the lug 13 with the shoulder formed by the recess 7 85 and a corresponding engagement of the lug 12 with the shoulder formed by the recess 6. When thus supported within the frame opening, it is obvious that the engagement of the box lugs and frame recesses described, will 90 operate to effectually lock the box in connection with the frame and prevent its movement either inward or outward. It will be observed that in the construction of the frame 1, I have provided a greater thickness 95 of metal above the openings & and below the same, thereby insuring greater strength where the same is needed.

By the construction which I have described, it will readily be understood that not only is a strong and durable construction of truck frame provided, but that means are embodied for interchangeably connecting with said truck frame separately formed journal boxes. It is well known that where integrally formed truck side frames and journal boxes are employed, great difficulty is experienced in securing perfect castings, such for instance as the difficulty of so casting such an integral formation as to over- 110

come the shrinking stresses and produce the boxes in their proper alignment; the difficulty of drawing patterns and the difficulty resulting from the necessary employment of 5 complicated cores. Another difficulty arising from constructions of this kind, is that any breakage or injury to the journal box necessitates the substitution of an entirely new truck frame and it is also well known 10 that where separately formed truck side frames and journal boxes have been connected by bolts and other separate attaching devices, such bolts are often broken from the effect of sudden jars or jolts to which a car is 15 ordinarily subjected. These difficulties are obviously overcome by the construction herein shown and described and in addition thereto, the form and construction of the bearing nuts or heads of the side frame, is 20 such as to impart great strength to the same.

What I claim, is:

1. The combination with an integrally formed truck side frame having openings through each end at right angles with the 25 direction of the length of said frame, and journal boxes adapted to be received and rigidly supported in said openings.

2. The combination with an integrally

formed truck side frame having openings through each end thereof extending at right 30 angles to the direction of the length of the frame, and means for detachably locking, said journal boxes into rigid engagement with said frames.

3. The combination with an integrally 35 formed truck side frame having openings through each end thereof extending at right angles with the direction of the length of the frame, of journal boxes, and means formed integral with said journal boxes for engaging 40 said truck frame and holding said boxes rigidly in connection therewith.

4. The combination with a truck side frame having openings through the integrally formed end portions thereof, said openings 45 extending at right angles with the direction of the length of the frame, and journal boxes adapted to be received by and rigidly held in said openings.

In testimony whereof I affix my signature 50 in presence of two witnesses.

CHARLES B. GOODSPEED.
